R. S. Kelley.

ATTORNEY.

UNITED STATES PATENT OFFICE

GIDEON SUNDBACK, OF MEADVILLE, PENNSYLVANIA, ASSIGNOR TO HOOKLESS FASTENER COMPANY, OF MEADVILLE, PENNSYLVANIA, A CORPORATION OF PENNSYLVANIA

FASTENING DEVICE

Application filed February 5, 1930. Serial No. 426,013.

My invention relates to fastening devices and particularly to that class of such devices having interlocking portions adapted to be successively brought together at an angle to each other and progressively interlocked. A slider may be used for the purpose of interlocking and releasing the parts of the fastener or in some forms of my invention, the fastening may be accomplished simply by the fingers.

It is an object of my invention to provide an improved fastening device of the type specified which shall be exceedingly flexible and which can be manufactured at a low cost. A further object is to provide an improved fastener of the class specified having projections on one side interlocking with recesses on the other side and in which reinforcing means extend across said recess.

A further object is to provide an improved fastener made of molded material with improved reinforcing means embedded in the material.

Other objects and advantages of the invention will more fully appear during the course of the following specification.

In the accompanying drawings I have shown for purposes of illustration several embodiments which my invention may assume in practice. In these drawings:

Fig. 1 is a perspective view of a portion of a fastening device embodying my invention.

Fig. 2 is a longitudinal sectional view through the fastening device shown in Fig. 1.

Fig. 3 is a view of a modified form of the fastener being closed by the fingers.

Fig. 4 is a plan view of a further modification.

Fig. 5 is a transverse sectional view on line 40 5-5 of Fig. 4.

The fastening device illustrated in Fig. 1 comprises a pair of flexible stringers or body members 6 and 7 which may be attached to the edges of the article to be fastened in any convenient manner. Each of the separable body portions or stringers comprises a web section 8 and interlocking portions 9 and 10 projecting from the web portions and preferably integrally connected to the same. In 50 the preferred embodiment both the web

portions and the interlocking portions are molded out of a suitable rubber composition. The interlocking portion 10 is provided with a substantially cylindrical recess 11 extending its entire length and the interlocking section 9 has formed integral therewith a series of spaced substantially cylindrical projections 12 which are adapted to fit loosely in the recess 11. A series of metal reinforcement elements extend transversely across the recess 11 and have their ends 14 and 15 bent at a right angle to provide more secure anchoring means. These metal reinforcing members are provided at regularly spaced intervals along the interlocking portion and fit into the spaces 16 between the projections 12 on the cooperating fastener member.

In order to bring the flexible interlocking portions into proper relationship for interlocking, a slider 17 comprising a strip of metal bent to generally U-shape is fitted over the edges of the fastener members. It will be noted that the outside contour of the interlocking portions 9 and 10 is such as to provide shallow grooves 18 and the slider is suitably curved to fit into these grooves and be guided by them in its travel along the fastener elements. The edges of the slider are turned up as indicated at 19 and 20 so that they will not dig into the rubber but rather 80 ride smoothly over it and guide the parts of the fastener together. In the form illustrated in Fig. 1, the web portions 8 of the fastener extend in the same direction and thus a fastener is provided which is very suitable for 85 many applications such as handbags, pocketbooks, etc.

However, in other applications such as garments, it is desired to have the web portions extend in opposite directions and in Fig. 3 is disclosed a modification of the construction adaptable for such purposes. In this figure it will be observed that web portions 21 and 22 extend from opposite sides of the fastening members proper. In other respects, the fastener construction is identically the same as that illustrated in Figs. 1 and 2 except that instead of providing a slider for closing the fastener members, the fingers of the user may be employed for the purpose. The 100

thumb and one finger of one hand are engaged in the grooves 18 and run along the entire length of the fastener from one end to the other, thus locking the fastener in the same manner as the slider 17.

In either of the forms shown in Figs. 1 and 3, when it is desired to open the fastener it is simply necessary to take hold of the ends last to be closed and tear open the 10 fastener. The fastener may be very easily separated in this way and at the same time, will hold very securely against separation by a straight pull on the web portions of the fastener.

15 In operation it will be noted that the projections 12 and the walls of the recess 11 are made of very flexible material which will yield sufficiently to allow entrance of the projections into the recess and this is facilitated by bringing the parts together progressively so that only one portion at a time of the fastener is being connected. At the same time the reinforcements resist lateral flexing apart of the recess walls and thus materially 20 strengthen the fastener.

25 In Fig. 4 is shown a modification of the construction so as more closely to resemble the well known slide fastener. In this construction the recess 23 corresponding to the recess 11 faces outwardly from the edge of the interlocking portion 24 and cooperates 30 with projections 25 corresponding to the projections 12 on the interlocking portion 26 of the mating fastener element. These interlocking portions are joined to webs 27 and 28 which serve to connect the fastener to the article to be fastened. It will be noted 35 that because of the greater thickness of the interlocking portions as compared to the webs 27 and 28 square shoulders 29 are provided and these shoulders form a convenient means for receiving and guiding the slider 30. This slider may be of a type similar to those employed in commercial slide fasteners and is illustrated as having a pair of 40 spaced wings 31 and 32 disposed on opposite sides of the interlocking portions and provided with flanges for cooperation with the shoulders 29. As is usually the case in such 45 sliders, the wings are connected by an integral wedging and spacing portion 33 at the rear end of the slider and a Y-shaped channel with diverging portions at the rear end of the slider is thus provided for receiving the stringers or fastener members and 50 guiding them into and out of interlocking relation. The metal reinforcing members are provided in this fastener just as in the types illustrated in Figs. 1 and 3. This 55 slider preferably has an integral reinforcing yoke 34 and one side of the slider the yoke is formed to provide suitable bearings 35 for receiving the pull device 36. If desired the projections 25 may have extensions 60 37 which engage behind the wires 13 and

strengthen the fastener against lateral separation. It will thus be seen that in this modification of my invention there is provided a fastener generally similar to the slide fastener which is well known at the present time.

As a result of my invention it will be observed that an improved fastening device has been devised which is very flexible and sufficiently strong for many purposes. The fastener construction readily adapts itself to manufacture by a molding operation and thus can be very easily constructed from rubber or similar material. The wire reinforcing elements may be embedded conveniently in the rubber during the molding operation.

75 While I have in this application specifically described three embodiments which my invention may assume in practice, it will be understood that these embodiments are merely for the purposes of illustration and description and that various other forms may be devised within the scope of my invention as defined in the appended claims.

80 What I claim as my invention is:

1. In a multiple fastener, a pair of flexible strips, interlocking projections on one of said strips, a projection-receiving recess on the other of said strips, and reinforcing means 90 extending directly across said recess to resist separation of the walls thereof.

2. In a multiple fastener, a pair of flexible strips, interlocking projections on one of said strips, a projection-receiving recess on the other of said strips, and metal reinforcements extending across the mouth of said recess to resist separation of the walls thereof.

3. In a multiple fastener, a pair of flexible members, interlocking projections on one of said members, resilient means forming a projection-receiving recess on the other of said members, and reinforcing wires extending 100 across said recess to resist separation of the walls thereof.

4. In a multiple fastener, a pair of flexible portions, interlocking projections along the edge of one of said portions, the other of said portions having a recess formed integrally therewith for receiving said projections, and spaced metal wires extending transversely 110 across said recess to resist separation of the walls thereof.

5. In a multiple fastener, a pair of flexible strips composed of rubber, interlocking projections on one of said strips, means integral with the other of said strips forming a projection-receiving recess, and reinforcing means extending across said recess to resist separation of the walls thereof.

6. In a multiple fastener, a pair of flexible strips, interlocking projections along the edge of one of said strips, a continuous recess extending along the other of said strips for receiving said projections, and metal reinforcements extending transversely across 120 130

said recess and arranged to enter between said projections when the fastener is closed.

7. In a multiple fastener, a pair of flexible strips, interlocking projections along the edge of one of said strips, a continuous recess extending along the other of said strips for receiving said projections, metal reinforcements extending transversely across said recess and arranged to enter between said projections when the fastener is closed, and extensions on said projections engaging behind said reinforcements when the fastener is closed.

In testimony whereof I affix my signature.
